UNITED STATES PATENT OFFICE.

JOSIAH WARREN ROBERTSON, OF ST. PAUL, INDIANA.

SCYTHE SNATH.

Application filed May 31, 1924. Serial No. 717,154.

To all whom it may concern:

Be it known that I, JOSIAH WARREN ROBERTSON, a citizen of the United States, residing at St. Paul, in the county of Decatur 5 and State of Indiana, have invented certain new and useful Improvements in Scythe Snathes, of which the following is a specification.

My said invention consists in an improved 10 metal scythe snathes appropriately shaped and provided with fittings adapted to hold a scythe in a secure but at the same time adjustable manner.

Referring to the accompanying drawings, 15 which are made a part hereof and on which similar reference characters indicate similar parts,

Figure 1 is an elevation of my improved 20 scythe snath showing a scythe hung there- to,

Figure 2, a similar view of the lower part thereof on an enlarged scale,

Figure 3, a section on line 3—3 of Figure 2, and

Figure 4, a section on line 4—4 of Figure 1.

Figure 5, a fragmentary side view.

In the drawings, reference character 10 indicates the scythe snath which is in the 30 form of a metal bar, preferably of steel, here shown as flat in cross section and bent over appropriately formed into the standard shape of the ordinary wooden snath, although, of course, it may be of any shape 35 found suitable. Near its lower end, it is provided with two holes spaced a distance apart which holes are adapted to receive bolts 11 and 12.

The scythe 13 is of any approved type, the 40 heel or shank being formed with a perforation through which the bolt 11 extends and said shank has an outwardly projecting tang 14 at its extreme point. A clamp member 15 with a perforation near its lower end and a transverse slot near its upper end, located 45 so as to receive the bolts 11 and 12 respectively, is secured to the lower end of the snath on said bolts with the shank of the scythe between said clamp member and the snath, the tang 14 engaging a perforation in the clamp member at a point adjacent bolt 12. A brace 17 is secured to the snath at a point adjacent nib 19, as at 18, by riveting or otherwise and has an eye at its lower 50 end which engages bolt 12 (Fig. 3) underneath clamp member 15.

In hanging the scythe on the snath it is adjusted to secure the desired "hang" by swinging the same on the bolt 11 with the clamp member 15 within the limits permitted by slot 16, and when the desired hang is obtained the parts are rigidly clamped in position by tightening the nut on bolt 12 and also the nut on bolt 11.

The scythe snath is provided with the 65 usual nibs 18 and 19 of wood or other appropriate material positioned and secured on bolts which extend through longitudinal perforations in said nibs and through perforations in the snath to which they are 70 clamped by nuts on said bolts with metal washers interposed between the nuts and ends of the nibs. The snath is formed so that said nibs may be correctly positioned thereon to bring the parts into the most 75 advantageous relative position for use. In use, the scythe is hung to the snath, and adjusted, by manipulation of the bolts 11 and 12 and the clamping member 15, as will be readily understood from the foregoing 80 description.

By this construction I obtain a very rigid and durable scythe snath and one to which the scythe can be attached in a very rigid and secure manner while also providing for 85 adjusting its "hang". Various changes and modifications of the device will be obvious to those skilled in the art and therefore I do not limit myself to what is shown in the drawings and described in the specification 90 but only as indicated in the appended claims.

Having thus fully described my said invention, what I claim as new and desire to 95 secure by Letters Patent, is:

1. In a scythe the combination of a bowed snath formed of a bar of metal having a brace adjacent one end for holding said bar in bowed position, a plate having a heel with a tang projecting laterally therefrom, said heel having an aperture for pivots carried by said snath, a clamping element secured on the lower portion of said snath and clamping said heel against said snath, said clamping member having an aperture similar to the aperture in said heel at one end and having an opening adjacent its other end receiving said tang, a common pivot for the clamping member carried by said snath and extending through the aperture in said heel and clamping element, a slot in said clamping element adjacent its upper end,

- and a fastening element carried by said snathe extending through said slot and through one end of said brace, substantially as set forth.
5. 2. In a scythe, the combination of a snathe, a blade having a heel with a laterally projecting tang, a clamping member secured on the lower portion of said snathe and clamping said heel against said snathe, said clamping member having an opening receiving said tang, a common pivot for the lower ends of said clamping member and extend-

ing through said heel, a slot in the upper end of said clamping member, a bolt carried by the snathe and extending through said slot and a brace connected to said bolt and the upper portion of the snathe, substantially as set forth.

In witness whereof, I have hereunto set my hand at Indianapolis, Indiana, this 24th day of May, A. D. nineteen hundred and twenty-four.

JOSIAH W. ROBERTSON.
